UNITED STATES PATENT OFFICE.

GEORGE A. TINNEMAN, OF CLEVELAND, OHIO.

REMOVABLE GAS-BURNER FOR OVENS.

1,062,670.

Specification of Letters Patent.

Patented May 27, 1913.

Application filed June 17, 1910. Serial No. 567,357.

To all whom it may concern:

Be it known that I, GEORGE A. TINNEMAN, a citizen of the United States of America, residing in Cleveland, county of Cuyahoga, and State of Ohio, have invented certain new and useful Improvements in Removable Gas-Burners for Ovens, of which the following specification is a full, clear, and exact description, reference being had 10 to the accompanying drawings, forming a part thereof.

My invention relates more particularly to a removable gas burner and air spreader or distributor therefor, especially adapted for 15 the conversion of the oven in a combined gas and coal range; the object thereof being to provide a removable burner adapted to heat the oven equally when gas is employed as a fuel, in association with means for furnishing 20 ample air supply, without interfering with the coal range, and for protecting the floor or bottom of the oven.

The invention as embodied and herein described comprises a perforated frame, which 25 serves to supply air throughout the length of the burner. This in turn is superposed upon a suitable non-conducting shield for protecting the floor of the oven, while a depending pipe makes connection with the gas- 30 supply and air mixer.

Further details and the advantageous features of this construction will be explained in connection with the accompanying drawings, wherein:—

35 Figure I. is a perspective view of a combined gas and coal range, partly broken away, and showing the oven open and equipped with my improvements; Fig. II. is a vertical sectional view, showing the gas- 40 connection partly broken away, and the burner, spreader, shield and a portion of the stove or range-bottom in section; Fig. III. is a perspective view of the unitary burner, air distributor, shield and removable connecting-pipe or sleeve; Fig. IV. is a similar 45 view of the bottom duct and protective member for the gas-connection, and Fig. V. shows the removable cover therefor.

Throughout the several figures of the 50 drawings, I have employed the same characters of reference to indicate similar parts.

My improvements are shown in connection with certain additional features of my invention described and claimed in my application, Serial No. 545,347, filed February 23rd, 1910, for patent upon combined gas

and coal ranges. Therein, as shown in the present drawings, the fire box *a* is positioned upon the left of the range, and the oven *b* is adjacent thereto; affording inner walls for the down-draft flues surrounding said oven upon three sides. The chimney pipe *c* is connected with said flues *d* *d'* *d''*, beneath the oven *b*. A tubular collar *e* extends through flue *d''* connecting the same with the external air and inclosing the gas connection *f* for the removable oven burner. The duct or collar *e* is adapted to be closed by the removable cover *e'* when coal is used for heating the range.

For converting the oven to one heated by gas, it is necessary only to take out the cover *e'*, and insert the combined burner, air-spreader and shield unit of my invention. Therein the burner *g* comprises an elongated casting perforated upon either side and extending substantially the depth of the oven when inserted therein. A depending pipe *g'* removably fits over the gas connection *f*, and extends down into the duct or collar *e*. 80 With this collar there connects the perforated air spreader *h* lying beneath the burner *g*, which is thereby adapted to furnish ample air supply even to the extremities of the burner which are distantly situated from said duct *e*.

A sheet iron frame *i* comprises, with the sheet of asbestos-board *j*, a non-conductive shield for the bottom of the oven; these members being suitably screwed or bolted from beneath, to the longitudinal oven burner *g*, and, accordingly, insertible in and removable from the oven *b*, as a unitary structure. Necessarily the oven bottom must be thin and highly conductive, so that the heat from the bottom flue may readily reach the oven when coal is used for fuel. In order to prevent downward radiation, and consequent waste of heat when the fuel used is gas, I preferably associate the non-conductive shield above described, with the gas burner, so that said shield may practically cover the oven bottom and protect it from the heat.

An important consideration when the range is used with coal, or other solid fuel, is the uniform heating of the oven bottom from beneath. This cannot occur where a large air-duct is provided, which, moreover, obstructs the bottom flue. It also affords access for an undesirable supply of cold air to the oven. Accordingly, I employ in con-

nection with an air-duct of relatively small size, and suitably positioned to furnish the necessary supply of air, my novel air-distributer, which is intimately associated with the burner, to produce effective combustion immediately above the oven bottom.

The false-bottom *k* is insertible within the oven immediately above the burner *g*, and serves to deflect the flame laterally at either side, while the non-conducting shield *j* not only protects the bottom or floor of the oven from the excessive heat, but prevents its downward radiation and consequent loss.

The purpose of the perforated air-supply-spreader *h* will be appreciated when one considers that the extremities of the burner are at such distance from the central air-supply, that complete combustion would be practically impossible. Accordingly, the perforations *h'* in the chambered air spreader follow generally the contour, first of the duct *e* and then of the longitudinal burner *g*, whereby the air entering through said duct is deflected to supply the entire length of the burner and effect complete combustion. If this were not done, either a number of ducts would be required for a long burner, or only that portion of the flame immediately adjacent to the air duct would be supplied with sufficient oxygen to effect combustion.

The convenience afforded by the combined burner, air spreader and shield in converting the oven of a combined coal and gas range to one heated by gas, will be readily appreciated, since the insertion of this unit and of the false bottom, will at once permit gas to be used, while the removal of these parts and the covering of the duct, will readily convert said oven.

Having now explained the preferred embodiment of my invention, I claim as new and desire to secure by Letters Patent, the following:

1. A removable member for convertible ranges, comprising an oven-bottom protecting-plate or shield, a burner-member superimposed on the shield, and a gas-supply connection for the burner-member, substantially as set forth.

2. A removable oven-burner, comprising a gas connection, a tubular member fitting the same, an associated non-conducting shield, and a superposed burner-member adapted to rest with said shield upon the bottom of the oven, substantially as set forth.

3. In a removable burner-device for convertible-ovens, the combination with a combined air-spreader and elongated burner adapted to be removably positioned upon the oven bottom, of a gas connection, and

an air duct extending to said oven, and respectively connecting with the burner and air-spreader; said duct being of materially less area, as compared with the area defined by the burner and air spreader, substantially as set forth.

4. A removable gas burner unit, comprising a non-conducting shield, a superposed air-spreader extending transversely thereof, a superposed burner extending substantially the length of the air-spreader, in combination with a stationary collar adapted to connect the air-spreader with the external air, and a gas connection inclosed therein above which connection the burner removably fits, substantially as set forth.

5. The combination with an elongated gas-burner, of an intermediate gas-connection therefor, a collar or duct of restricted area, and an air distributer extending substantially the length of the burner and connecting intermediately with said duct; said burner and air-distributer comprising a unitary removable structure, substantially as set forth.

6. The combination with an elongated gas-burner, of an intermediately-connected inferior air-duct of restricted area, and an air-spreader or distributer extending substantially the length of the burner, and having perforations conforming substantially to the contour of said burner and duct; said burner and air-distributer comprising a unitary removable structure, as set forth.

7. The combination with an elongated oven-burner, of a connecting gas-supply pipe, an air-spreader extending substantially the length of the burner and having perforations or openings for distributing the air peripherally thereto; said burner and air-spreader being removably positioned above the oven bottom, and a connection of restricted area for said spreader adapted to supply air thereto, substantially as set forth.

8. In a device of the class described, the combination with a gas-connection, of an elongated burner-member removably fitting thereon, an elongated air-spreader extending beneath said burner, and an air-duct of materially less area than the air-spreader with which it connects to form a continuous conduit to distribute the external air around the burner-member, substantially as set forth.

In testimony whereof I affix my signature in presence of two witnesses, this fifteenth day of June, A. D., 1910.

GEORGE A. TINNERMAN.
